Application June 2, 1947, Serial No. 751,757

12 Claims. (Cl. 93—36)

1

This invention relates to machines for inserting carrying handles in collapsed cartons of the type used by consumers for carrying bottled beverages of various sizes and makes from store to home. Such type of carton is shown, for example, in Patent No. 2,345,563.

In its broader aspects it is an object of the invention to provide a machine for inserting generally U-shaped or C-shaped carrying handles in collapsed cartons having openings therein adapted to receive the handles, the machine having means for simultaneously feeding the cartons and the handles into position with respect to each other so that the openings are in alignment with the ends of the handles and adapted to receive them, and means for flexing the cartons in such a manner that the handles will enter the openings therein and be held in position for use when the cartons are unflexed.

More specifically, it is an object of the invention to provide such a machine wherein suitable mechanism is provided for feeding cartons and handles into position with respect to each other so that handle-receiving openings in the cartons are properly brought into alignment with the handles and adapted to receive them, together with a pair of opposed jaws which are spring loaded to move toward each other and cam controlled to move away from each other, between which the cartons must pass so that they will be flexed along their longitudinal axes, and two oppositely disposed rotating members having openings therein adapted to engage the ends of the handles to push them in the direction of the cartons so that their ends will enter the openings and be snapped into position and so held therein when the cartons are unflexed.

Other objects of the invention will in part be obvious and will in part appear hereinafter.

For a fuller understanding of the nature and objects of the invention reference should be had to the following detailed description taken in connection with the accompanying drawings, in which:

Fig. 1 is a side elevational view of a machine embodying the present invention;

Fig. 2 is a front elevational view, partly in section and somewhat enlarged, taken along the lines 2—2 of Fig. 1 and looking in the direction of the arrows;

Fig. 3 is a top plan view of the machine depicted in Fig. 1, also somewhat enlarged;

Fig. 4 is a transverse sectional view of the central portions of the machine depicted in Fig. 2 illustrating preferred means for flexing a col-

2

lapsed carton along its longitudinal axis and rotatable members receiving the ends of the handle members simultaneously to snap the handles into position in openings in the carton;

Fig. 5 is an elevational view of one of a pair of opposed rotary handle-receiving and inserting members illustrating its actuating function against an end portion of a handle;

Fig. 6 is a perspective view of one of a pair of opposed rotary cam members attached to the main drive shaft to control the outward movement of the carton flexing of the machine against spring tension, and to limit the inward movement of the jaws as they are flexing the collapsed carton;

Fig. 7 is a perspective view of a collapsed carton illustrating by means of the arrows the direction of movement of the jaws in flexing the carton along its longitudinal axis and the downward movement of a pair of rotary handle inserting members for urging the handles into certain openings of the carton; and

Fig. 8 is a perspective view of the carton handle inserted in an erected carton ready for filling with bottled beverages.

Referring more particularly to the drawings, it will be seen that there is a magazine 10 for cartons mounted on a frame 11. Adjacent the magazine 10 are two oppositely placed, vertically extending chutes 12 for downwardly feeding a stack of handle members 20 from a horizontal magazine 13 which, preferably, is disposed above the magazine 10 for the cartons. Preferably, a conventional weight and follower type of feed arrangement 14 is used for moving the lined stack of handles in magazine 13 toward the chutes 12.

Vertically mounted in spaced apart relation in front of the chutes 12, 12 are shafts 15, 15.

Each has a miter gear 16, 16 attached at each end. These miter gears are each meshed with corresponding miter gears 17, 17 journaled horizontally on the frame of the machine. Secured to each miter gear 17, 17, is a rotatable handle control member 18, 18, each of these members having an opening or cut-out portion 19 therein (see Fig. 5). The opening in each rotatable member 18 is of a size to accommodate the end of one of the handles 20 shown in the drawings.

As indicated on the drawings, and as will more fully appear hereinafter, the top rotatable members 18, 18, individually receive each advancing handle 20 as it passes along the hopper 13 and moves it downwardly into the chutes 12, 12. The lower rotatable members 18, 18 similarly receive

the ends of each handle 20 in their respective openings to depress the handles 20 into the cartons, also as will more fully appear hereinafter.

The train of miter gears is actuated by gears 21, 21 mounted on a shaft 22. These gears mesh with further miter gears secured to stub shafts on which the lower miter gears are mounted hence actuate the mechanism for feeding and controlling the downward movement of the handles 20.

The shaft 22 is suitably journaled in bearings 23, 23 and receives its movement from a split main drive shaft 24 through the gear train indicated generally at 25. The shaft 24 is mounted in suitable roller bearings 26, 26 and is driven by a chain 27 passing around a sprocket 28 thereon, chain 27 being trained around another sprocket 29 on a driving motor.

Also mounted upon the split drive shaft 24 are two face cam members 30, 30 (see Fig. 6). Each of these cams has a dwell therein indicated generally at 31. The function of these cams is to control the outward movement and to limit the inward movement of the carton flexing jaws about to be described. In order to do this the cam surfaces each bear against cam follower rollers 32, 32, which are in turn secured to reciprocating jaws 33, 33.

The jaws are moved inwardly toward each other by the actions of springs 34, 34 mounted in the frame 11 of the machine when the rollers 32, 32 enter the dwells 31, 31 in the cams 30, 30.

Attached to the inner end of each half of the main drive shaft 24 is a crank arm 35 and a connecting rod 36 is pivoted to the arms at one end, the other end of rod 36 being pivoted to a carton selecting or pusher plate 37. Plate 37 is mounted to reciprocate along a bed 38 in the frame of the machine. The pusher member 37 and bed 38 preferably are disposed immediately beneath the carton magazine 10.

The machine herein illustrated is particularly useful for cartons of the type shown in Figs. 7 and 8 of the drawings. These cartons are of the type made from a single blank of die-cut and scored boxboard material, glued and folded together in collapsed condition. Such a carton necessitates a handle, and preferably any suitable type of handle such as that indicated at 20 in the drawings, and of a generally U-shaped or C-shaped construction, is utilized, the handles preferably being made of metal. In order to insert these handles into the carton it is necessary to provide openings or apertures of some kind therein and these are preferably located along the ridge of such cartons as indicated at 39, 39 (see Fig. 7 of the drawings).

In operation the pusher plate 37 reciprocates underneath the carton magazine 10 as the plate is actuated by the crank arm 35 and connecting rod 36 from the main drive shaft 24. With each forward movement a carton is moved in the direction indicated by the arrows (Figs. 1 and 3) and comes to rest between the jaws 33. This will bring the openings 39, 39, of the carton directly in alignment with the handles 20 in chutes 12, 12, in a position to receive the handle upon the succeeding operations which follow. As each handle in the bottom of the stack in the chutes 12, 12, is brought into this predetermined position with respect to the carton, the latter is flexed upwardly along its longitudinal axis by the inward movement of the jaws 33. This is accomplished in timed relation to the movement of the main drive shaft 24 by means of the cams 30, 30, and springs

34, 34. It will be seen that as the crank 35 and main drive shaft 24 continue to rotate the face of each cam 30, 30 will bear against the rollers 32, 32 in such a manner that the jaws 33, 33 to which the rollers are connected, will be moved in an outward direction, i. e. away from each other. However, as the cams 30, 30 continue to rotate, the rollers 32, 32 ultimately enter and pass through the dwell 31 in each cam 30, being forced thereagainst by the action of the springs 34, 34. The springs force the jaws 33, 33 toward each other and the carton between them is flexed or bowed upwardly along its longitudinal axis as indicated in Figs. 4 and 7 of the drawings. Bed 38 prevents downward flexure of the carton, so that the latter can only flex upwardly under lateral compression of its edges. This bowing or flexing action is sufficient to bring the openings 39, 39 of the carton in direct registry with the free ends of the handle 20. Simultaneously with this action the gear train 25, connected to the drive shaft 24, continues to rotate the shaft 22, controlling the rotation of the miter or bevel gears 16, 16 through the gears 21, 21. This causes the lower rotating members 18, 18, to rotate toward each other. As the vertical end portions of each handle 20 enter the openings 19, 19 in the rotatable members 18, 18, the rotating movement thereof will force the handle downwardly so that the free ends thereof will enter the openings 39, 39 in such a manner that the ends of the handles 20 will be snapped into position in the carton as it is unflexed. The unflexing occurs when the cam rollers 32, 32 have passed through the dwells 31, 31, of the cams 30, 30, and risen on the high portions of the cams 30, 30, forcing the rollers and jaws 33, 33 away from each other, thereby unflexing the carton and securely holding the handle member and carton in interlocked relation.

The upper rotating members 18, 18 of the handle feeding mechanism are, as heretofore explained, identical in construction to the lower rotating members 18, 18. Their function is to receive the advancing charge of handles and control their downward travel in chutes 12, 12 by exerting pressure to maintain them in proper succession to the lower portion of the column of handles.

It will thus be seen that the objects hereinbefore set forth may readily and efficiently be attained, and since certain changes may be made in the above construction and different embodiments of the invention could be made without departing from the scope thereof, it is intended that all matter contained in the above description or shown in the accompanying drawings shall be interpreted as illustrative and not in a limiting sense.

Having described my invention what I claim as new and desire to secure by Letters Patent is:

1. A machine for inserting carrying handles in collapsed cartons having openings therein adapted to receive said handles, comprising in combination, means, including a carton selecting member to separate individual cartons from an accumulated stack of cartons, for simultaneously feeding said cartons and said handles into position with respect to each other so that said openings are in alignment with said handles and adapted insertably to receive the same, and means adapted to flex said cartons and to actuate said handles so that the handles will enter said openings and be held therein when said cartons are unflexed.

2. A machine for inserting carrying handles in collapsed cartons having openings therein adapted to receive said handles, comprising in combination, means, including a reciprocating carton pusher plate actuated by a crank shaft to select individual cartons from a group of cartons, for simultaneously feeding said cartons and said handles into position with respect to each other so that said openings are in alignment with said handles and adapted insertably to receive the same, and means adapted to flex said cartons and to actuate said handles so that the handles will enter said openings and be held therein when said cartons are unflexed.

3. A machine for inserting carrying handles in collapsed cartons having openings therein adapted to receive said handles, comprising in combination, means, including a carton feeding magazine and a handle hopper in adjacently arranged relation, and a carton selector and a handle selector for simultaneously feeding said cartons and said handles into position with respect to each other so that said openings are in alignment with said handles and adapted insertably to receive the same, and means adapted to flex said cartons along their longitudinal axes and to actuate said handles so that the handles will enter said openings and be held therein when said cartons are unflexed.

4. A machine for inserting carrying handles in collapsed cartons having openings therein adapted to receive said handles, comprising in combination, means, including a carton selecting member to separate individual cartons from an accumulated stack of cartons, for simultaneously feeding said cartons and said handles into position with respect to each other so that said openings are in alignment with said handles and adapted insertably to receive the same, and means, adapted to flex said cartons along their longitudinal axes and means to actuate said handles in a direction transversely thereof so that the handles will enter said openings and be held therein when said cartons are unflexed.

5. A machine for inserting carrying handles in collapsed cartons having openings therein adapted to receive said handles, comprising in combination, means, including a carton selecting member to separate individual cartons from an accumulated stack of cartons, for simultaneously feeding said cartons and said handles into position with respect to each other so that said openings are in alignment with said handles and adapted insertably to receive the same, and means, including a pair of opposed jaw members, adapted to flex said cartons and to actuate said handles so that the handles will enter said openings and be held therein when said cartons are unflexed.

6. A machine for inserting carrying handles in collapsed cartons having openings therein adapted to receive said handles, comprising in combination, means, including a carton selecting member to separate individual cartons from an accumulated stack of cartons, for simultaneously feeding said cartons and said handles into position with respect to each other so that said openings are in alignment with said handles and adapted insertably to receive the same, and means, including a pair of opposed jaw plates reciprocably movable toward and away from each other, adapted to flex said cartons and to actuate said handles so that the handles will enter said openings and be held therein when said cartons are unflexed.

7. A machine for inserting carrying handles in collapsed cartons having openings therein adapted to receive said handles, comprising in combination, means, including a carton selecting member to separate individual cartons from an accumulated stack of cartons, for simultaneously feeding said cartons and said handles into position with respect to each other so that said openings are in alignment with said handles and adapted insertably to receive the same, and means, including a pair of opposed jaws which are spring loaded to move said jaws toward each other, adapted to flex said cartons and to actuate said handles so that the handles will enter said openings and be held therein when said cartons are unflexed.

8. A machine for inserting carrying handles in collapsed cartons having openings therein adapted to receive said handles, comprising in combination, means, including a carton selecting member to separate individual cartons from an accumulated stack of cartons, for simultaneously feeding said cartons and said handles into position with respect to each other so that said openings are in alignment with said handles and adapted insertably to receive the same, and means, including a pair of opposed jaws which are spring loaded to move toward each other and cam controlled to move away from each other, adapted to flex said cartons and to actuate said handles so that the handles will enter said openings and be held therein when said cartons are unflexed.

9. A machine for inserting carrying handles in collapsed cartons having openings therein adapted to receive said handles, comprising in combination, means for simultaneously feeding said cartons and said handles into position with respect to each other so that said openings are in alignment with the ends of the handles and adapted insertably to receive the same, means adapted to flex said cartons along their longitudinal axes, and means, including a pair of oppositely disposed handle engaging members adapted to actuate the handles so that the handles will enter said openings and be held therein when said carton is unflexed.

10. A machine for inserting carrying handles in collapsed cartons having openings therein adapted to receive said handles, comprising in combination, means adapted to flex said cartons and means, including two oppositely disposed rotating members having openings therein adapted to engage the ends of said handles and to actuate them in the direction of the cartons so that they will enter said openings and be held therein when said cartons are unflexed.

11. A machine for inserting carrying handles in collapsed cartons having openings therein adapted to receive said handles, comprising in combination, means for simultaneously feeding said cartons and said handles into position with respect to each other so that said openings are in alignment with said handles and adapted insertably to receive the same, means, including a pair of opposed jaws which are spring loaded to move toward each other and cam controlled to move away from each other so that the jaws are opened and closed in timed relation to flex said cartons so that the handles will enter the openings and be held therein when said cartons are unflexed, and means, including two oppositely disposed rotating members having openings therein adapted to engage the ends of said handles and to actuate them in the direction of the cartons

so that they will enter said openings and be held therein when said cartons are unflexed.

12. A machine for inserting U-shaped carrying handles in collapsed cartons of a type having openings therein adapted to receive said handles, comprising in combination, means for feeding said cartons and said handles toward a position with respect to each other in which said openings are in alignment with the ends of the handles and adapted insertably to receive the same, 10 means to flex said cartons upwardly at a medial zone between said openings and along their longitudinal axes, means to position said handles so that the ends of the handles will enter said openings and interlock therewith when said cartons 18

are unflexed, and a support engaged by the lowermost portion of said cartons during flexure and acting to insure that flexure takes place upwardly at said medial zone.
